ANTHONY ISKE, OF LANCASTER, PENNSYLVANIA:

Letters Patent No. 73,013, dated January 7, 1868.

IMPROVEMENT IN ALARM-LOCKS FOR DOORS.

The Schedule referred to in these Letters Patent and making part of the same.

TO ALL WHOM IT MAY CONCERN:

Be it known that I, ANTHONY ISKE, of Lancaster, in the county of Lancaster, in the State of Pennsylvania, have invented a new and improved mode of connecting a bell with an ordinary lock, constituting it a Combined Alarm-Lock and Door-Bell; and I do hereby declare that the following is a full, clear, and exact description of the construction and operation of the same, reference being had to the accompanying drawings making a part of this specification, in which—

Figure 1 is a view of the inside of an ordinary lock, with my improvements in place.

Figure 2, the several details shown separated.

Figure 3 shows the combination of the lock with the bell.

Figure 4, two bolts, shown to connect the bell with the key-hole plate, and also with the turning-knob, to act independently, if desired, by means of two connecting wires to the bell-lever.

The nature of my invention consists in providing an ordinary turning-latch and lock with an alarm-bell attachment, which can be easily connected or disconnected, in such a manner that when the knob of the door is turned either to the right or left, to open it, the alarm-bell will sound; as also any attempt to pull the plate aside that covers the key-hole, either for inserting a key or applying nippers, the alarm will be given; this plate also answering to ring the bell as an ordinary door-bell.

The lock and the bell used are of the ordinary kind in use, and form no part of my invention apart from the additional bolts and connection between the two.

To enable others skilled in the art to make and apply my invention, a brief explanation is only required, as the drawings clearly indicate the construction and application.

An additional hole is drilled into the casing-plates for the sleeve or pipe E, fig. 2, which sleeve has a projecting lever-arm, e, and a square central opening (constituting the sleeve E) for the square portion of the arm B, on the vibrating knob-plate, covering the key-hole. The key-hole plate A has a hole, a, for said arm, with an upper extended notch, through which the arm is thrust in a reverse position, so that the confining-peg P, beneath said arm B, will pass through the notch, and when the knob is turned down over the key-hole, the plate comes between the peg P and descending plate, with its knob b, and, while it allows the same to be drawn aside, it cannot be pulled out while on the door. There is also a hooked bolt, C, and tumbler or lever, D, actuated by the movements of the latch, as shown in fig. 1, (half size,) with the parts in place. The sleeve E has also a connection, resting between the shoulder m and peg o, on the hooked bolt C, by its raised lever e. Thus combined, the single bolt will act upon the lever or bell-hammer, both when the knob H is turned on the latch or the knob b drawn aside. By using separate bolts, fig. 4, and two connections, each may be acted independently of the other. Fig. 3 shows the wire, F, connected with the hook e, (extending outside the case of the lock,) and with the spring-lever and hammer of the bell G.

The operation is simple and readily understood. This arrangement is useful for various considerations. In front shops, when the attendant is employed in another room, the entrance of any one is at once announced. The door cannot be opened or unlocked without giving the alarm. The connection can be made with any kind of a bell, either upon the door or remote from it, or any number of bells.

I am aware that alarm-locks have been used before, where the alarm is actuated by the latch and lock-bolt, so that the lock-bolt will respectively connect or disconnect the alarm-lever with the latch-bolt, in which a rocking arm and slide-lever are used. Such I disclaim. I am not aware that an extra sliding bolt, with a hook projecting from the case, for connecting it to and disconnecting it from the bell-hammer, by means of a wire, substantially operated in the manner specified, nor of a sleeve for the armed cover of the key-hole for operating a bell, substantially in the manner described.

What I claim as my invention, and desire to secure by Letters Patent, is—

The combination and arrangement of one or two hooked bolts C, lever D, sleeve E, with the arm B, on the vibrating plate, with or without its knob b, when applied to a lock for the purpose of connecting the same with a bell or alarm, in the manner specified.

ANTHONY ISKE.
